DESIGN FOR AN ELECTRICALLY OPERATED BEAN HEATER

Herman E. Lacy, Chicago, Ill.

Application June 27, 1938, Serial No. 78,096

Term of patent 14 years

To all whom it may concern:

Be it known that I, Herman E. Lacy, a citizen of the United States, residing at Chicago, in the county of Cook and State of Illinois, have invented a new, original, and ornamental Design for an Electrically Operated Bean Heater, of which the following is a specification, reference being had to the accompanying drawing, forming part thereof.

Figure 1 is a side elevational view of an electrically operated bean heater showing my new design.

Figure 2 is a plan view of same with the cover thereof in open position.

I claim:

The ornamental design for an electrically operated bean heater, as shown and described.

HERMAN E. LACY.
